CLAIM

The ornamental design for an LED lamp module, as shown and described.

DESCRIPTION

FIG. 1 is a perspective view of an LED lamp module showing our new design;

FIG. 2 is a front view thereof, a rear view being identical with the front view;

FIG. 3 is a left side view thereof, a right view being a mirror image of the left side view;

FIG. 4 is a top plan view thereof;

FIG. 5 is a bottom plan view thereof;

FIG. 6 is a cross-sectional view taken along line 6—6 in FIG. 4;

FIG. 7 is an exploded perspective view showing the LED lamp module shown in FIG. 1 in an environment of use with a lens; and,

FIG. 8 is a perspective view showing the LED lamp module shown in FIG. 1 in an environment use with an LED lamp. The broken lines shown in the figures illustrate environmental structure and form no part of the claimed design.
